CLAIM

The ornamental design for a baking cup, as shown, and described.

DESCRIPTION

FIG. 1 is a perspective view of a baking cup showing my new design.

FIG. 2 is a front view of the baking cup;

FIG. 3 is a side view of the baking cup;

FIG. 4 is a top view of the baking cup;

FIG. 5 is a bottom view of the baking cup; and,

FIG. 6 is a perspective view of the baking cup in a use environment.

The broken line showing of the cups in FIG. 6 depicts environment and forms no part of the claimed design.

1 Claim, 6 Drawing Sheets
